HOLDER FOR STICK MATERIAL

Charles N. Coryell, Mamaroneck, N. Y.

Application October 19, 1931, Serial No. 569,662

7 Claims. (Cl. 206—56)

The invention relates to cosmetics, and more particularly to holders dispensing stick materials such as a lipstick.

According to a preferred form of the invention, 5 the holder comprises a holder tube in which is slidably mounted an operating member projecting from the bottom thereof. Within the holder tube is a U-shaped guide and slidably mounted within this guide is a carrier member holding the 10 lipstick or other stick material. Disposed outside of the U-shaped guide is a stiff spring band thin enough to bend around the lower end of the guide. This band is connected at one end to the operating member and at the other end to the 15 carrier member through a slot in the guide.

If desired, a cover may be hinged to the top of the holder tube, having a spring for urging the cover into open position. A spring catch may be provided also on the holder tube for holding the cover closed and if desired the catch may be 20 operated by the movement of the operating member.

The invention also consists in certain new and 25 original features of construction and combinations of parts hereinafter set forth and claimed.

Although the novel features which are believed 30 to be characteristic of this invention will be particularly pointed out in the claims appended hereto, the invention itself, as to its objects and advantages, and the manner in which it may be carried out, may be better understood by referring to the following description taken in connection with the accompanying drawings forming a part thereof, in which

Fig. 1 is a perspective of one form of holder in 35 closed position;

Fig. 2 is a perspective of the holder in open position with the lipstick advanced for use;

Fig. 3 is a vertical section through the holder;

Fig. 4 is a section on the line 4—4 of Fig. 3;

Fig. 5 is a plan view of the holder in the position shown in Fig. 3;

Figs. 6 and 7 are sections on the lines 6—6 and 7—7, respectively, of Fig. 3;

Fig. 8 is a perspective of the operating member by itself;

Fig. 9 is a perspective of the guide member by itself;

Fig. 10 is a perspective of the preferred form 50 of holder in open position;

Fig. 11 is a vertical section of the holder shown in Fig. 10; and

Fig. 12 is a detail illustrating the operating member.

In the following description and in the claims,

various details will be identified by specific names for convenience, but they are intended to be as generic in their application as the art will permit.

Like reference characters denote like parts in the several figures of the drawings. 5

In the drawings accompanying and forming part of this specification, certain specific disclosure of the invention is made for purposes of explanation, but it will be understood that the details may be modified in various respects without departure from the broad aspect of the invention. 10

Referring to the drawings, (Figs. 1-9), the holder comprises essentially the holder tube 10, cover 11, U-shaped guide 12, operating tube 13, 15 carrier member 14, holding lip-stick 15 and flexible ball 16.

The holder tube 10 is open at the bottom and has an inwardly projecting flange 20 at the top, 20 said flange having notches 21 for a purpose hereinafter described. At the top of the holder tube is also an aperture 22 for the catch, as hereinafter described.

The cover 11 is provided with an outwardly projecting portion 23 forming a recess for the 25 catch. The cover 11 is connected to the holder tube 10 by a hinge made up of lugs 25 secured to the cover (Fig. 5), lugs 24 secured to the holder tube, a pintle 26 and a wire spring 27 surrounding the pintle and having one end disposed 30 against the flange 20 and the other end passing through an opening in the wall of the cover, as indicated at 127 in Fig. 3. The spring 27 acts always to urge the cover to open position. 35

For holding the cover closed, a catch is provided having a spring portion 27 secured to the holder tube by rivet 28 and a lug 29 disposed in the opening 22. The spring 27 is biased to normally hold the catch in the position shown in Fig. 3. 40

The guide member 12 (Fig. 9) is provided with a slot 31 in one side thereof, each side having side flanges 131 forming side channels. At the bottom end of the guide member 12 the channels are closed by a wall 30 forming a tubular 45 guide at this point for the flexible band 16, as shown in Figs. 3 and 4. The guide member 12 may be made from sheet metal bent to the shape shown.

The operating member 13 (Fig. 8) has a 50 flanged bottom 33, an opening 34, a slot 35 to the inside of which is secured a plate 135 forming in effect a shallow recess to receive the spring 27 of the catch (Fig. 3).

The carrier 14 holds the lipstick 15 and is con- 55

nected to the flexible band 16 by rivet 36 passing through the slot 31. The band 16 passes through the guide portion 30, extending down one side of the guide and up the other to be secured to the operating tube 13 by a rivet 37 which passes through the opening 34 in the operating tube.

The U-shaped guide 12 is secured within the holder tube 10 by solder, indicated at 38 in Figs. 3 and 5, the side flanges 131 of the guide fitting in the notches 21 of the holder tube 10.

When the holder is closed, the operating member 13 is disposed substantially entirely within the holder tube 10 so that its wall member 135 holds the catch 29 in a position projecting out of the opening 22 so that the catch is disposed in the recess 23, holding the cap 11 closed.

To use the holder, the operating tube 13 is pulled downwardly to the position shown, for instance, in Fig. 3. This allows the catch 29 to spring inwardly, releasing the cover 11, which springs to the open position. At the same time, moving the flexible band 16 downwardly on one side forces the other side thereof upwardly to feed the lipstick 15 outwardly.

To close the holder, the operating tube 13 is moved inwardly, this serving to move the lipstick 15 also inwardly. The cover 11 is then closed by hand, the catch 29 yielding sufficiently to engage the recess 23.

Referring now to the form preferred at this time, illustrated in Figs. 10, 11, and 12, it will be noted that the construction is quite similar to that illustrated in Figs. 1 to 9, inclusive. In the preferred form, however, instead of using an operating tube a flat operating member or rod 47 is used. Also, the holder tube indicated by 40 is closed at the bottom by a closure 51 soldered to or tightly pressed onto the lower end of the holder tube.

The operating member 47 has a curved finger-engaging portion 48 and a notch 50 closed on one side by a plate 49. The operating member 47 passes through an opening in the bottom closure 51 and is secured to the operating band 45.

The plate 49 serves to engage the spring catch 46 when the former is in its uppermost position to hold the cap 41 closed in the same manner as described in connection with Figs. 1 to 9. The cap 41 is mounted upon the holder tube 40 by a spring hinge in the same manner as the cap in Figs. 1 to 9. The U-shaped guide 44 is similar in construction to the U-shaped guide 12 except that the projections 32 are no longer necessary. The U-shaped guide is held in position between the closure 51 and the annular inturned flange 52.

The holder 43 holds the lipstick 42 which is operated by the band 45. The band 45 is connected at one end to the plate 49 and at the other end to the carrier member 43 thru the slot 144.

It is thought the operation of this holder is obvious from the construction thereof and from the explanation of Figs. 1 to 9. To open the holder it is only necessary to pull down upon the operating member 47. This causes the catch 46 to move inwardly which in turn allows the cap 41 to spring open. Downward movement of the operating member 47 causes the lipstick 42 to move upwardly and vice versa.

The preferred form of holder has the advantages of being less expensive to manufacture and of obviating the soldering of the U-shaped guide

to the upper end of the holder tube. Furthermore, the provision of the bottom closure 51 assists in imparting a more balanced appearance to the holder when closed, since it offsets the cap on the other end.

Thus a holder for stick material has been provided which is neat and attractive in appearance and simple in construction and operation. The feed of the lipstick can be nicely controlled to project the stick material to any desired distance. The automatic opening of the cover makes the holder easier to use.

While certain novel features of the invention have been disclosed and are pointed out in the annexed claims, it will be understood that various omissions, substitutions and changes may be made by those skilled in the art without departing from the spirit of the invention.

What is claimed is:

1. In a holder, a holder tube, an operating tube telescoping within said holder tube, a U-shaped guide within said operating tube and secured to said holder tube at the upper end thereof, a carrier within said guide, a flexible band between said guide and said operating tube and connected at one end to said carrier and at the other end to said operating tube, said band being bent to pass down one side of said guide and up the other.

2. In a holder, a holder tube open at top and bottom, an operating tube closed at bottom and open at top telescoping within said holder tube, a U-shaped guide within said operating tube and secured to said holder tube at the upper end thereof, a carrier within said guide, one leg of said guide having a slot, a flexible band between said guide and said operating tube and connected at one end to said carrier through said slot and at the other end to said operating tube, said band being bent to pass down one leg of said guide and up the other.

3. In a holder, a holder tube open at top and bottom, an operating tube closed at bottom and open at top telescoping within said holder tube, a U-shaped guide within said operating tube and secured to said holder tube at the upper end thereof, a carrier within said guide, one leg of said guide having a slot, a flexible band between said guide and said operating tube and connected at one end to said carrier through said slot and at the other end to said operating tube, said band being bent to pass down one leg of said guide and up the other, a cap hinged to the top of said holder tube, spring means normally urging said cap into open position, a spring secured to said holder tube at its lower end, a catch on said spring for engaging said cap, said spring being engageable by said operating tube to place said catch in position for engagement by said cap.

4. In a holder for stick material, a holder tube having a substantially closed lower end with a small opening in said end, a carrier member within said holder tube, an operating rod projecting through said small opening and disposable between said carrier member and the side wall of said holder tube, and means for causing said carrier member to move upwardly when said operating rod is pulled downwardly.

5. In a holder, a holder tube having a bottom end wall provided with an opening, an operating rod passing through said opening and disposed within said holder tube at one side thereof, a U-shaped guide within said holder tube between said operating rod and the other side of

said holder tube, a carrier within said guide, a flexible band between said guide and said holder tube and connected at one end to said carrier and at the other end to said operating rod, said band being bent to pass down one side of said guide and up the other.

6. In a holder, a holder tube open at the top and having a bottom end wall, said end wall having an opening at an edge thereof, an operating rod having a finger engaging part at the bottom thereof and passing through said opening, a U-shaped guide within said holder tube and disposed against said end, a flange at the top of said holder tube against which guide is also disposed, a carrier member within said guide, one leg of said guide having a slot, a flexible band between said guide and said operating rod and connected at one end to said carrier member through said slot and at the other end to

said operating rod, said band being bent to pass down one end of said guide and up the other.

7. In a holder, a holder tube having a bottom end wall with an opening in said end wall, an operating rod telescoping within said holder tube 5 and passing thru said opening, a U-shaped guide within said holder tube, a carrier within said guide, a flexible band between said guide and said operating rod and connected at one end to said carrier and at the other end to said operating rod, said band being bent to pass down one side of said guide and up the other, a cap hinged to said holder tube, spring means normally urging said cap into open position, a spring secured to said holder tube a catch on said spring for 10 engaging said cap, said spring being engageable by said operating rod to place said catch in position for engagement by said cap.

CHARLES N. CORYELL.
